UNITED STATES PATENT OFFICE.

JAMES C. BUCHANAN, OF WASHINGTON, DISTRICT OF COLUMBIA, ASSIGNOR TO RAPID TOBACCO STEMMER CO., OF BALTIMORE, MARYLAND, A CORPORATION OF DELAWARE.

TOBACCO-STEMMING MECHANISM.

Specification of Letters Patent.

Patented May 1, 1917.

1,224,848.

Application filed March 1, 1917. Serial No. 151,787.

To all whom it may concern:

Be it known that I, JAMES C. BUCHANAN, citizen of the United States, residing at Washington, in the District of Columbia, have invented certain new and useful Improvements in Tobacco-Stemming Mechanism; and I do hereby declare the following to be a full, clear, and exact description of the invention, such as will enable others skilled in the art to which it appertains to make and use the same.

My invention relates to improvements in tobacco stemming machines and more particularly to that class of tobacco stemmers in which the leaf lamina or blade is removed from the leaf stem by rotating knives. The principal object of my invention is to provide a mechanism of this class which will stem the leaves with greater effectiveness and efficiency than those machines heretofore employed. To accomplish this result, I have devised special rotating cutters which coöperate with a reciprocating knife and form a substantially triangular opening through which the stem of the leaf is drawn and each wall of said opening consists of a moving cutting edge, which cuts the lamina or blade from the stem, as the stem passes through said opening.

A further object of my invention is to provide a tobacco stemming machine with horizontally disposed disks having inclined peripheral teeth provided at their lower portions with cutting edges which form two of the walls of the triangular opening, the cutting edges of these rotating disks co-operating with a reciprocating knife mounted beneath the disks and forming the other wall of the triangular opening.

With the foregoing objects outlined and with other objects in view as will appear as the nature of the invention is better understood, my invention consists in the novel features hereinafter described in detail, illustrated in the accompanying drawing and more particularly pointed out in the appended claims.

Referring to the drawings;

Figure 1 is a detail perspective view of a portion of a stemming machine of the type set forth showing my improvements applied thereto.

Fig. 2 is a front view of a portion of said detail.

Fig. 3 is an enlarged top plan view of the 55 horizontally disposed disks.

Fig. 4 is an edge view of the same partly in section.

Figs. 5 and 6 are detail perspective views of the central portions of modified forms of 60 the reciprocating cutting knife.

Fig. 7 is a side view of the left hand disk and a portion of the leaf feeding belt and also a vertical sectional view of the horizontally disposed reciprocating knife. The 65 manner of stemming a leaf by my improved mechanism is shown by this figure.

In the drawings 1 represents the longitudinally disposed side bars of the stemming machine frame, which are provided with 70 longitudinally disposed slots 2 for the reception of bolts 3 that adjustably secure brackets 4 to the machine frame. Mounted upon the upper ends of the brackets is a horizontally disposed narrow cutting knife 75 provided with a forward cutting edge 5^a. The knife 5 is provided near its ends with transverse slots 6 through which extend bolts 7 that are employed to movably secure the knife to the brackets and permit the 80 knife to be reciprocated. The mechanism for reciprocating the knife comprises a cam 8 which is rigidly carried by a shaft 10, supported by a bracket 9, and the shaft is designed to be rotated by suitable mechanism 85 (not shown) from the stemmer drive. A spring 8^a has one of its ends connected to the knife 5 and its other end connected to the bracket 9, and this spring acts to maintain the end of the knife in contact with the 90 periphery of the cam 8.

Pivots secured to the stemming machine frame in the known manner, are ordinary brackets 11, the free ends 12 of which support vertical shafts 13 carrying at their 95 lower ends horizontally disposed disks 14, which are rotated by belts 15, that turn the pulleys 16. A suitable device such as a spring is used for holding the free ends 12 of the brackets 11 toward one another and 100 to permit them to separate slightly to accommodate leaf stems of varying thicknesses but as this feature forms no part of my improvement, I have not illustrated the same.

The disks 14 are provided with serrations or teeth 17, as illustrated in all the figures of the drawings, preferably inclined to the axes of the disks, as shown, and the 105

- disks are so driven that they rotate toward each other and toward the front of the machine, as indicated by the arrows. It will be seen that the disks rest upon the horizontally disposed knife 5 and that the cutting edge 5^a is arranged just forward of the axes of the disks 14, as shown in Fig. 7. During the operation of stemming the blade portions of the leaf pass below this 10 knife and the knife serves to support the stem, which passes over it. By adjusting the brackets 4 along the machine frame the forward edge of the knife 5 may be moved toward or away from the axes of the disks 14 and thus the amount of stem taken from the leaf, may be regulated.
- In stemming machines having horizontally disposed cutters, now in use, should a leaf be presented edgewise to the cutters, 20 there is a tendency to strip the stem on one side only, or not at all, and to overcome this defect, I have cut away the lower edges of the teeth of the disks, as shown at 18. These cut away portions 18 form with the 25 knife 5, a triangular opening 19, each wall of which is a movable cutting edge, and said opening permits the passage of the stems while the cutting edges successfully strip the lamina or blade therefrom.
- 30 The leaves are carried between the cutters by the usual feed belts 20, which engage the butts of the leaves as shown in Fig. 1, and as the leaves are fed rearwardly, the inclined teeth 17 will draw the tobacco 35 downwardly so that the edges of the cut away portions of the forwardly revolving teeth, together with the horizontal knife, will cut the leaf from its stem. This operation is facilitated by the vibration of the 40 knife 5, which causes the leaf to be thrown from side to side so that it is positively engaged by the cutters and sheared.
- In Figs. 5 and 6, I have illustrated modified forms of the horizontally disposed cutting knife, in one of which I have provided a V-shaped cutting recess 40 and in the other a U-shaped recess 50, and in use the recessed portion of the knife is adapted to 45 align with the meeting edges of the disks.
- 50 What I claim and desire to secure by Letters Patent is:—
1. In a tobacco stemming machine, a pair of horizontally disposed disks having peripheral teeth provided at their lower edges with cut away portions forming cutting edges, said disks being arranged in the same plane with their edges adjacent, and mechanism for rotating said disks.
  2. In a tobacco stemming machine, a pair of horizontally disposed disks having peripheral teeth provided at their lower edges with cut away portions forming cutting edges, said disks being arranged in the same plane with their edges adjacent, and mechanism for rotating said disks, and a hori-

zontally disposed knife located below said disks.

3. In a tobacco stemming machine, a pair of horizontally disposed disks having peripheral teeth provided at their lower edges 70 with cut away portions forming cutting edges, said disks being arranged in the same plane with their edges adjacent, and mechanism for rotating said disks, and a vibratory horizontally disposed knife located below 75 said disks.

4. In a tobacco stemming machine, a pair of horizontally disposed disks having peripheral portions provided with cutting surfaces, said disks being arranged in the same 80 plane with their edges adjacent, and mechanism for rotating said disks, and a vibratory knife arranged below the disks and co-operating with said disks.

5. A tobacco stemming machine comprising 85 horizontally disposed disks having peripheral teeth provided at their lower edges with cut away portions forming cutting edges, said disks being arranged in the same plane with their edges adjacent, means for 90 rotating said disks, a horizontally disposed knife arranged beneath said disks, and co-operating with the same, and means for vibrating said knife.

6. A tobacco stemming machine comprising 95 horizontally disposed disks having peripheral teeth provided with cutting edges, said disks being arranged in the same plane with their edges adjacent, means for rotating said disks, a horizontally disposed knife 100 located beneath said disks and co-operating with the same, means for vibrating said knife, and means for adjusting said knife relative to said disks whereby a greater or less amount of stem may be removed from 105 the leaf.

7. A tobacco stemming machine comprising horizontally disposed disks having peripheral teeth provided with cutting edges between which the stems of the leaves are 110 adapted to be drawn, said disks being arranged in the same plane with their edges adjacent, means for rotating said disks, a horizontally disposed knife located beneath said disks and provided with a recess which 115 normally aligns with the meeting edges of the disks, and means for vibrating said knife.

8. In a tobacco stemming machine, a pair of opposed disks having peripheral teeth cut 120 away at one end to form cutting edges, means for rotating said disks, and means for drawing a tobacco leaf between said disks in position to have the cutting edges 125 stem or strip the same.

9. In a tobacco stemming machine, a pair of parallel shafts mounted for movement toward and away from each other, a horizontal disk mounted on each of said shafts, means for rotating said disks, means for 130

- 5 drawing a tobacco leaf between said disks, and a horizontally disposed knife with a forwardly presented edge disposed across the lower faces of said disks.

5 10. In a tobacco stemming machine, a pair of parallel shafts mounted for movement toward and away from each other, a horizontal disk mounted on each of said shafts and having peripheral teeth cut away at one end to form cutting edges, means for rotating said disks, means for drawing a tobacco leaf between said disks in position to have the cutting edges stem or strip the same, and a horizontally disposed 10 knife with a forwardly presented cutting edge disposed across the lower faces of said disks.

15 11. In a tobacco stemming machine, a pair of parallel shafts mounted for movement toward and away from each other, a horizontal disk mounted on each of said shafts and having peripheral teeth inclined to the axis of the disk, means for rotating said disks, means for drawing a tobacco leaf between said disks, and a horizontally disposed knife having a forwardly presented cutting edge disposed across the lower faces of said disks.

20 25 30 35 40 45 50 55 60 65 70 75 80 85 90 95 990

12. In a tobacco stemming machine, a pair of parallel shafts mounted for movement toward and away from each other, a horizontal disk mounted on each of said shafts and having peripheral teeth inclined to the axis of the disk and cut away at one end to form cutting edges, means for rotating said disks, means for drawing a tobacco leaf between said disks in position to have the cutting edges stem or strip the same, and a horizontally disposed knife with a forwardly presented cutting edge disposed across the lower faces of said disks.

13. In a tobacco stemming machine, a pair of parallel shafts mounted for movement toward and away from each other, a horizontal disk mounted on each of said shafts, means for rotating said disks, means for drawing a tobacco leaf between said disks, a horizontally disposed knife having a forwardly presented cutting edge arranged beneath said disks, and means for vibrating the knife longitudinally across the path of the leaves.

14. In a tobacco stemming machine, a pair of parallel shafts mounted for movement toward and away from each other, a horizontal disk mounted on each of said shafts and having peripheral teeth cut away at one end to form cutting edges, means for rotating said disks, means for drawing a tobacco leaf between said disks in position to have the cutting edges stem or strip the same, and a horizontally disposed knife with a forwardly presented cutting edge disposed across the lower faces of said disks, and means for vibrating the knife longitudinally across the path of the leaves.

15. In a tobacco stemming machine, a pair of parallel shafts mounted for movement toward and away from each other, a horizontal disk mounted on each of said shafts, means for rotating said disks, means for drawing a tobacco leaf between said disks, and a horizontally disposed knife with a forwardly presented edge disposed across the lower faces of said disks, the knife being adjustable from front to rear.

16. In a tobacco stemming machine, a pair of parallel shafts mounted for movement toward and away from each other, a horizontal disk mounted on each of said shafts and having peripheral teeth inclined to the axis of the disk and cut away at one end to form cutting edges, means for rotating said disks, means for drawing a tobacco leaf between said disks in position to have the cutting edges stem or strip the same, and a horizontally disposed knife with a forwardly presented cutting edge disposed across the lower faces of said disks, the knife being adjustable from front to rear.

17. In a tobacco stemming machine, a pair of parallel shafts mounted for movement toward and away from each other, a horizontally disposed disk mounted on each of said shafts and having peripheral portions provided with cutting edges, means for rotating said disks, means for drawing a tobacco leaf between said disks, and a horizontally disposed knife located beneath said cutters and provided with a recess which normally aligns with the meeting edges of the disks.

In testimony whereof I affix my signature.

JAMES C. BUCHANAN.
